UNITED STATES PATENT OFFICE.

CHARLES F. CLOSE, OF WATKINS, NEW YORK.

CARPET-RAG LOOPER.

SPECIFICATION forming part of Letters Patent No. 773,001, dated October 25, 1904.

Application filed July 23, 1903. Serial No. 166,762. (No model.)

To all whom it may concern:

Be it known that I, CHARLES F. CLOSE, a citizen of the United States, residing at Watkins, in the county of Schuyler and State of New York, have invented a new and useful Carpet-Rag Looper, of which the following is a specification.

This invention relates to carpet-rag loopers; and one of the principal objects of the device is to provide means for confining the device within a small space when not in use and which will be so constructed that the looper-blade may be folded down upon the base, so as not to be liable to be accidentally inserted into the finger or injure adjacent persons.

A further object of the invention is to provide means for holding the blade in its proper operative position with relation to the base.

Further objects and advantages, as well as the novel details of construction, will be specifically referred to hereinafter, reference being had to the accompanying drawings, in which—

Figure 1 is a perspective view of one form of the invention ready for use. Fig. 2 is a vertical longitudinal sectional view of the same. Fig. 3 is a perspective view of a modified form of the invention, and Fig. 4 is a vertical longitudinal sectional view of the same.

The reference-numeral 1, Fig. 1, designates a base which is illustrated as being in the form of a plate 2, having a terminal depending spur 3, which may be driven into the table or support, whereby the base-plate will be secured rigid with relation thereto. At the end remote from the spur are parallel arms 4 and 5, having curved terminals which form bearings 6 and 7 for the oppositely-disposed lugs or projections 8, carried by the looper-blade. The blade is illustrated as comprising a suitable strip 9, having a terminal point of introduction 10 in the form of a cam provided by bending one end, 11, of the blade at an angle to the blade and then bending it back upon itself to constitute a cam which will have a bearing against the yielding finger 12, formed with the base-plate. Thus the looper-blade will be firmly held in either of its extremes of adjustment to which it may be placed.

In the modified form illustrated in Figs. 3 and 4 the plate 1^a is provided with side longitudinal flanges which are curved to form barrels 14 and 15 for the reception of the terminals of the arms 4^a and 5^a, which are connected together terminally by a cross-bar 16, around which the end 17 of the looper-blade 55 9 is secured, being constructed similar to the blade 9 and operates in substantially the same manner.

It will be understood that the looper-plate is to be used in substantially the same manner that all loopers now generally employed are used, and it is not deemed necessary at this time to give a detail description of the same.

I claim—

1. In a carpet-rag looper, a plate having a terminal spur, curved terminals having bearings, a spring-tongue between the terminals, and a looper-blade bent back upon itself to contact with the tongue and said blade being pivoted in the bearings in the curved terminals.

2. In a carpet-rag looper, a base having a terminal spur, and a looper-blade carried by the base and having an offset terminal bent back upon itself and bearing upon the base.

3. In a carpet-rag looper, a plate provided with parallel longitudinal slits at one end to provide a spring-tongue, bearings carried by the plate, a blade journaled in the bearings and having a terminal cam comprising an extension at right angles to the blade and bent back upon itself to lie flush with and bear against the tongue when in a vertical position so as to maintain a rigid contact therewith.

4. In a carpet-rag looper, a base, and a looper-blade carried by the base and having an offset terminal bent back upon itself and bearing upon the base.

In testimony that I claim the foregoing as my own I have hereto affixed my signature in the presence of two witnesses.

CHARLES F. CLOSE.
